UNITED STATES PATENT OFFICE.

AMOS F. DIXON, OF NEWARK, NEW JERSEY, ASSIGNOR TO WESTERN ELECTRIC COMPANY, OF NEW YORK, N. Y., A CORPORATION OF ILLINOIS.

ELECTROMAGNET.

1,097,400.

Specification of Letters Patent. Patented May 19, 1914.

Application filed December 18, 1912. Serial No. 737,540.

To all whom it may concern:

Be it known that I, AMOS F. DIXON, a citizen of the United States, residing at Newark, in the county of Essex and State 5 of New Jersey, have invented a certain new and useful Improvement in Electromagnets, of which the following is a full, clear, concise, and exact description.

This invention relates to electromagnets, 10 and is particularly adapted for use in telephone signal bells, although not exclusively limited to such use.

The object of this invention is to provide 15 an electromagnet structure of the above type in which the adjustment of the armature is easily and positively accomplished, and whose efficiency is high and the construction simple.

To the above end a novel form of link 20 structure is provided in combination with an armature support and adjusting means. The construction of the magnet coils is likewise such as to insure the most efficient operation.

25 This invention will be fully understood from the following description taken in connection with the accompanying drawing in which—

Figure 1 shows the invention embodied in 30 a telephone signal bell, one magnet coil of which is shown partly in section, and Fig. 2 is an expanded view in perspective showing the construction and arrangement of the novel features.

35 A pair of magnet coils 5 are each provided with a core 6 of magnetic material. The magnet coils are supported at one end in any suitable manner to a supporting piece 7, and at the other end each core is provided 40 with a contracted portion 8. A pair of non-magnetic link pieces 9 are adapted to be placed upon the contracted portions 8 of the core 6 and are held in place by metallic disks 10. These disks are preferably of 45 greater diameter than the diameter of the cores. The disks 10 are welded to the pole pieces 6 in any suitable manner, thus forming a low reluctance connection therebetween. The softening of the end of the pole 50 pieces 6 and the pressure applied to the parts during the welding operation insures a rigid connection for said link pieces 9. The disks 10 being of greater diameter than that of the cores 6 provide pole faces in

which the magnetic density is less than that 55 in the cores, which construction has been found to be the most efficient.

The link pieces 9 are each provided with slots 15 and 16, the former serving as guides and seats for tongues 17 of a flexible arched 60 armature support or bridge 18. A coupling 19 is provided which has tongues 20 adapted to engage the slots 16. The coupling 19 is likewise provided with a threaded opening 21 for engaging the threads of an adjusting screw 22. The arched armature support is provided with a pair of lugs 25 between which the armature 26 is pivotally mounted. The armature 26 may carry a 70 clapper 30 for contacting with gongs 31.

The adjustment of the armature 26 is secured by means of the adjusting screw 22, which is provided with a shouldered head 32 and passes through an opening 33 in the arched armature support 18 and an opening 75 34 in the armature 26. The head 32 engages the edges of the opening 33 in the armature support 18, and as the adjusting screw is threaded into the coupling 19, the support 18 is flexed to bring the armature 80 nearer the poles of the cores 6. When the adjusting screw, on the other hand, is threaded out of the coupling 19, the resiliency of the arched support 18 causes the armature 85 to be moved away from the poles of the cores 6.

What I claim is:

1. In combination, a pair of magnet cores, a link piece for each said core, means for securely connecting said cores and link 90 pieces, a coupling for said link pieces, a bridge coöperating with said link pieces, an armature carried by said bridge, and means engaging said coupling to hold said coupling in place and for adjustably moving 95 said armature by flexing said bridge.

2. In combination, a pair of magnet cores, a link piece for each said core, means for securely connecting said cores and link pieces, a flexible bridge engaging said link 100 pieces, an armature carried thereby, and means for adjusting said armature by flexing said bridge.

3. In an electromagnet the combination of a pair of cores, a link piece for each said 105 core, disks for securely connecting said cores and link pieces, a coupling engaging said link pieces, an armature support likewise

engaging said link pieces, and an adjusting screw coöperating with said coupling and armature support whereby said support is adjustably movable.

4. In combination a pair of magnet cores, a link piece for each said core, a coupling connecting adjacent ends of said link pieces, a bridge extending between the outer ends of said link pieces, a member connecting

said coupling and said bridge, and an armature mounted upon said bridge. 10

In witness whereof, I hereunto subscribe my name this 17th day of December A. D. 1912.

AMOS F. DIXON.
